UNITED STATES PATENT OFFICE.

LOUIS W. WITRY, OF WATERLOO, IOWA, ASSIGNOR TO WATERLOO GASOLINE ENGINE COMPANY, OF WATERLOO, IOWA.

DRIVING CONNECTION FOR MAGNETOS.

1,218,822.

Specification of Letters Patent. Patented Mar. 13, 1917.

Application filed May 24, 1916. Serial No. 99,564.

To all whom it may concern:

Be it known that I, LOUIS W. WITRY, a citizen of the United States of America, and a resident of Waterloo, Blackhawk county, Iowa, have invented certain new and useful Improvements in Driving Connections for Magnetos, of which the following is a specification.

My invention relates to improvements in driving-connections for magnetos, and particularly for those employed in combination with electric igniters of internal-combustion engines, and the object of my improvement is to furnish means for adjustably setting and securing the connection between the driving-means and the magneto so that the magneto may be set to actuate the igniter at a desired time.

This object I have accomplished by the means which are hereinafter described and claimed, and which are illustrated in the accompanying drawings, in which:

Figure 1 is a side elevation of a magneto and my improved adjustable driving-connection therefor as connected to driving-means, parts of each being in partial section.

Fig. 2 is a front elevation of the driving-connection as mounted on the driving-means, and disassembled from the magneto.

Fig. 3 is a detail perspective view of the laterally-adjustable linking-sleeve, and Fig. 4 is a detail perspective view of one of the clamping-members for the adjustable disk.

Similar numerals of reference denote corresponding parts throughout the several views.

Referring to Fig. 1, the numeral 1 denotes a magneto, having a driven-shaft 2 alined with a driving-shaft 16 adapted to be rotated by means not shown. The magneto is adapted to be installed on an internal-combustion engine in circuit with the igniter thereof and set to break the circuit in the usual manner. The driving-connections between the two shafts 2 and 16 are of the universal-coupling type and can be set at any angle desired to permit the magneto to cooperate with the igniter as may be desired.

The driving-connection comprises the following parts, as operatively associated with each other and with the said driving- and driven-shafts:

The end of the shaft 2 is diminished to seat a coupling-sleeve 4 at 19, and has oppo-

sitely-located grooves to seat lugs 3 on said sleeve. The opposite face of the sleeve 4 is transversely troughed at 5, at right angles to the grooves on said shaft 2. The numeral 13 denotes a disk splined on the diminished end 15 of the driving-shaft 16, concentrically, and having on its left-hand face a low raised central boss 14. A shallow concave circular plate 8 is fitted rotatably over and upon the boss 14, and has a raised central part 7 of relatively small diameter, which latter has a pressed-out transverse diametral ridge 6. This ridge 6 is fitted slidingly in the end-grooves 5 of the sleeve 4, whereby the driving-shaft 16 may still rotate the driven-shaft 2, although the shafts may be out of alinement.

I have supplied the following-described novel means for adjustably securing the plate 8 upon the boss 14 of said disk 13. The numeral 9 denotes a flat rectangular clamping-member having one end bent to one side at 11, and having at its opposite longitudinal edges the rectangular parts or spacers 17 bent in the same direction as the part 11, the parts or spacers 11 and 17 contacting with the face of the disk 13 just without the boss 14 to permit the other flat end of the member to overlie and contact with the adjacent face of said boss. The member 9 is orificed at 18 in line with a screw hole in the disk 13, and a screw 10 is passed through said alined orifices, to clamp the plate 8 tightly in frictional engagement with the boss 14. Two of these clamping-devices are used, oppositely, and it is merely necessary to loosen the screws to permit the plate 8 to be turned sufficiently before being re-secured, to place the connected parts of the magneto in a proper angular relation to the movable parts of the igniter, relative to advancing or retarding the ignition of the fuel in the combustion-chamber of the engine. It will be observed that the adjustment is perfect, and that the parts are so accessible as to render the adjustment easy, wherever the magneto is located.

Having described my invention, what I claim as new, and desire to secure by Letters Patent, is:

A driving-connection for a magneto, comprising in combination with a driven-shaft of a magneto and a driving-shaft, a clutch-member coupled to said driven-shaft, said clutch-member having an annular concave

coaxial disk-part, a disk fixed on and coaxial with the driving-shaft of larger diameter than the first-mentioned disk-part and having a concentric boss fitting within the cavity of the latter, clamping-bodies contacting with adjacent parts of said disks and having oppositely-located projections spacing them from the second-mentioned disk, and means for releasably securing said 10 clamps compressibly upon the first-men-

tioned disk-part to hold the first-mentioned disk-part in adjustable frictional driving-engagement with the other disk-part.

Signed at Waterloo, Iowa, this 8th day of May, 1916.

LOUIS W. WITRY.
